UNITED STATES PATENT OFFICE.

AUGUST ROBERTI, JR., AND EDWARD L. ROBERTI, OF LOS ANGELES, CALIFORNIA.

NON-STRETCHING VENTILATED MATTRESS.

1,180,432.

Specification of Letters Patent. Patented Apr. 25, 1916.

Application filed February 18, 1915. Serial No. 9,193.

To all whom it may concern:

Be it known that we, AUGUST ROBERTI, Jr., and EDWARD L. ROBERTI, citizens of the United States, both residing at Los Angeles, 5 in the county of Los Angeles and State of California, have invented a new and useful Non-Stretching Ventilated Mattress, of which the following is a specification.

Our invention relates to mattresses, and 10 the first object of the invention is to provide a mattress which will permanently retain its shape without spreading of the mattress due to a flattening of the tufting so that extra initial allowance for tufting is unnecessary.

15 The second object of the invention is to provide ventilating spaces so that the filling has a regular supply of fresh air.

The third object of the invention is to do away with the external tufts common 20 to the ordinary form of mattress and to substitute therefor a flat surface. This results in a much more comfortable mattress than the standard form and one that is more sanitary, the ordinary form of tufts tending to 25 collect dirt.

The fourth object of the invention is to provide tufting means or tie members between the upper and lower tick which are entirely concealed within the mattress and 30 entirely protected. This is important as the ordinary form of exposed tufts are very often torn or worn off.

The fifth object of the invention is to provide a tufting or tie means which will 35 secure the filling against lateral displacement or shifting within the tick. This is important as there is a decided tendency for the filling to be forced away from the center by a person lying on the center of the mattress, 40 so that after long use hollows and ridges appear in the mattress.

The sixth object of the invention is to provide a reinforced tick so that relatively 45 cheap material can be used without danger of the tick wearing or stretching. This reinforcement is preferably run across the warp, this being the weak direction of the ticking material.

The seventh object of the invention is to 50 provide a mattress having a flat surface and an even thickness so that full elasticity of the filling is utilized and maintained.

Further objects and advantages will be made evident hereinafter.

In the drawing: Figure 1 is a plan view 55 of our invention applied to a mattress, and Fig. 2 is an enlarged section on the plane x^2-x^2 of Fig. 1, showing a mattress with portions of the filling removed to better illustrate the invention.

In this particular embodiment of our invention, an upper ticking member 11 and a lower ticking member 12 are secured together by a boxing 13, the three members 11, 12 and 13 forming an inclosed tick in 65 which is placed the filling material 14. The filling may be hair, cotton felt, silk floss, or kapok, or any similar material. Before the mattress is made up and the members 11, 12 and 13 are sewed together, 70 reinforcing strips 15 and 16 are sewed to the members 11 and 12 by means of seams 17 and 18, tabs 19 being sewed on top of the strips 16 and tabs 20 being sewed on top of the strips 15. Eyelets 22 are then secured through the member 11 and the strips 15, and eyelets 21 are secured through the member 12 and the strips 16. The eyelets are so placed that the tabs 19 and 20 naturally lie over the eyelets as shown at A and 80 B in Fig. 2. The filling is then forced into place in the direction of the arrow shown in Fig. 2, this movement of the filling forcing the tabs up against the eyelets as shown at A and B in Fig. 2.

85 After the mattress has been filled and the tick closed, the operator proceeds to put in the ties 23. These ties are formed of twine 24 and are put in place in the following manner: A double pointed mattress needle 90 25 is used, the twine 24 being threaded through an eye 26 near one end 27 of the needle. The end 27 is passed through an eyelet 22, through a tab 20, through the filling 14, through a tab 19 and out through an eyelet 21, the needle being drawn through the tabs 19 and 20 and the filling 14, and the twine 24 also being drawn through forming the first strand 28 of a tie. The opposite end 29 of the needle 25 is then passed 95 through the eyelet 21, the same tab 19, the filling 14 and the tab 20 and out through the eyelet 22, the needle 25 and the twine 24 being drawn through to form the second strand 100 30 of a tie. A mattress knot 31 is then 105 formed on the end 32 of the first strand 28 about the second strand 30 and this knot is pulled into the interior of the mattress,

the tabs 19 and 20 being pulled into the position C—D of Fig. 2. The end 33 of the second strand is then cut off outside the mattress. The operation is then repeated, 5 ties 23 being formed between each of the tabs 19 and 20 until all the tabs are tied together in the position C D.

The reinforcing strips 16 and 17 run across the warp thread of the ticking and 10 produce a tick that will not stretch and which will permanently retain its shape, thus accomplishing the first object defined above. The eyelets 21 and 22 remain open allowing air to be drawn in and forced out 15 of the mattress, thus accomplishing the second object.

As the tabs 19 and 20 and the ties 23 are entirely within the mattress all external ties or tufts are omitted, and the surface of the 20 mattress is a substantially flat surface, there of course being a slight depression over each tab. The third object is thus accomplished. The same construction provides the protected tuft construction mentioned as the 25 fourth object.

In the ordinary form of mattress having twine ties only, there is very little anchorage for the filling which may be forced aside. In our invention the tabs 19 and 20 30 are pulled down into the body of the filling 14 and their broad surfaces securely anchor the filling against lateral displacement, this being the fifth object.

By the use of the reinforcing strips 16 and 35 17, the sixth object of the invention is accomplished, and the seventh object of the invention is accomplished by the use of the needle through the eyelets.

While we have illustrated and described 40 our invention as applied to a mattress, it is evident that it may be applied to any form of furniture where cushions are desired, or to vehicles, or other articles having such cushions. The term mattress is therefore to 45 be understood to include not only mattresses, but all similar devices.

We claim as our invention:

1. A mattress comprising an upper tick member, a lower tick member, boxing secured to said members in such a manner as 50 to form an inclosed tick, filling for said tick, ties secured to the inner surface of said members connecting said upper and lower tick members at a plurality of points, and 55 eyelets in said tick members through which said ties may be put in place.

2. A mattress comprising an upper tick member, a lower tick member, boxing secured to said members in such a manner as 60 to form an inclosed tick, filling for said tick, upper tabs secured to said upper tick member, lower tabs secured to said lower tick member, said tabs projecting into said filling, ties for connecting each upper tab with

a corresponding lower tab, and eyelets in 65 said tick members through which said ties may be put in place.

3. A mattress comprising an upper tick member, a lower tick member, boxing secured to said members in such a manner as 70 to form an inclosed tick, filling for said tick, upper tabs secured to said upper tick member, lower tabs secured to said lower tick member, said tabs projecting into said filling, string ties each sewn through an 75 upper and a lower tab and knotted in such a manner as to form a closed loop connecting said upper and lower tabs, and eyelets in said tick members through which said ties may be put in place.

4. A mattress comprising an upper tick member, a lower tick member, boxing secured to said members in such a manner as to 80 form an inclosed tick, filling for said tick, reinforcing strips running across the inner surfaces of said tick members and secured thereto, upper tabs secured at intervals to said reinforcing strips on said upper member, lower tabs secured at intervals to 85 said reinforcing strips on said lower member, ties for connecting said tabs in pairs, and eyelets in said tick members through which said ties may be put in place.

5. A mattress comprising an upper tick member, a lower tick member, boxing secured to said members in such a manner as 90 to form an inclosed tick, filling for said tick, reinforcing strips running across the inner surfaces of said tick members and secured thereto, upper tabs secured at intervals to said reinforcing strips on said upper member, lower tabs secured at intervals to 95 said reinforcing strips on said lower member, string ties each sewn through an upper and a lower tab and knotted in such a manner as to form a closed loop connecting 100 said upper and lower tabs, and eyelets in said tick members through which said ties may be put in place.

6. In a cushion having a flexible upper 110 tick member, tabs secured to said member and projecting into the interior of the cushion, ties for anchoring said tabs to the lower structure of the cushion, and eyelets in said tick member so place that said ties can be 115 secured to said tabs therethrough, each of said eyelets being located in the upper tick immediately beside one of said ties.

7. A flexible cover for cushions or mattresses comprising a tick, tabs secured to the 120 inner side of said tick, anchoring means for said tabs, and an eyelet in said tick above each of said tabs, said eyelets being so located that the anchoring means may be secured to said tabs therethrough.

8. A flexible cover for cushions or mattresses comprising a tick, a reinforcing strip secured to the inner side of said tick, tabs

secured to said reinforcing strip, anchoring means for said tabs, and eyelets in said tick, each of said eyelets being so located with reference to one of said tabs that said anchoring means may be applied to said tabs through said eyelet.

In testimony whereof, we have hereunto

set our hands at Los Angeles, California, this 1st day of February, 1915.

AUGUST ROBERTI, JR.
EDWARD L. ROBERTI.
